UNITED STATES PATENT OFFICE.

GEORGE O. BERGSTROM, OF NEENAH, WISCONSIN, ASSIGNOR TO BERGSTROM BROTHERS & CO., OF SAME PLACE.

DESIGN FOR A HEATING-STOVE.

SPECIFICATION forming part of Design No. 22,910, dated November 14, 1893.

Application filed September 2, 1893. Serial No. 484,809. Term of patent 7 years.

To all whom it may concern:

Be it known that I, GEORGE O. BERGSTROM, a citizen of the United States, residing at Neenah, in the county of Winnebago and State 5 of Wisconsin, have invented a new and original Design for a Heating-Stove, set forth in the accompanying specification, reference being made to the accompanying photograph of a stove having said design, which is made a 10 part of this specification.

The design consists of numerous raised ornaments and perforations which are placed upon the several parts of the stove as herein described.

15 The design for the stove top section 1, consists of the cap plate 2, lower top plate 3, and intermediate top plate 4, all shaped, ornamented, proportioned and arranged together so as to present substantially the appearance 20 herein shown.

The design for the cap plate 2, consists of the oval edged plain surfaced border *a*, and the convexly curved surface *b*, ornamented with the scrolls *c*, said scrolls inclosing the 25 perforations *c'*, all shaped and arranged substantially as herein shown.

The design for the lower top plate 3, consists of the convexly curved smooth faced band *d*, having underneath the same the vertically arranged, round bottomed ornaments 30 *e*, the convexly curved molding *f*, and above the band *d*, the convexly curved surface *g*, having thereon the scroll ornamentation *g'*, all shaped and arranged together substantially 35 as represented.

The intermediate top 4, consists of the inwardly beveled lower border *h*, having arranged above the same the vertically arranged round topped ornaments *e'*, harmonizing with 40 the ornaments *e*, underneath the band *d*.

The design for the door frame plate 5, consists of the plain outline of the frame having the oval border *i*, at each upper corner of said plate the scrolls *j*, at each lower corner of the 45 scrolls *j'*, all arranged and shaped substantially as shown.

The design for the stove doors 6, consists of the convexly curved outer edge *k*, ornamented with the ornaments *e''*, which are 50 similar in appearance but shorter and harmonize with the ornaments *e*, and *e'*, above

described, the doors having also the interior scroll ornaments *l*, covering both sections of the door, said scrolls having the perforations *l'*, near their upper ends, and having 55 located centrally of said doors and within said scroll a circular raised tablet *m*, having a plain border *m'*, said doors having also the scroll shaped latch *n*, extending inward to the aforesaid tablet, and the fluted ornamental 60 latch keeper *n'*, all shaped and arranged substantially as shown and described.

The design for the fire pot ring, 7, consists of the nearly perpendicularly arranged outer flange *o*, surmounted by the convexly curved 65 surface *o'*, having at each side of the door frame plate the semi-circular ornaments *p*, all being shaped and arranged in position substantially as shown.

The design for the foot rail 8, consists of 70 the oval outlined and transversely oval surfaced rail having a plain smooth surface *q*, at each side of the stove front, said foot rail having near the corners of the stove the scrolls *r*, and the rail being suspended from the upper ends of the curved arms *s*, which are provided upon their upper ends with a wide overhanging flange *s'* having a scroll *t*, said latter scrolls overlapping the scrolls, *r*, aforesaid, 75 all being shaped and arranged substantially as set forth.

The design for the stove base 9, consists of the horizontal top plate *u*, the inwardly straight beveled base band *v*, and the convexly curved section *v'*, having at each corner of said base the heart shaped ornament *w*, the depending ornaments *w'*, and the scrolls *w''*, the two front scrolls being connected with the molding *v''*, all arranged and shaped 80 substantially as shown.

The design for the base flange 10 consists of the convexly curved surface *x*, a border *x'* at the upper edge thereof, the sides of the stove having the scroll ornaments *y*, and upon its front the scroll *y'*, and the perforations 95 *y''*, inclosed by the half circles *y'''*, and the scrolls *y''''*, all being arranged and shaped substantially as shown.

The design for the stove legs 11 consists of the outwardly and inwardly curved and transversely oval surfaced legs having near their upper ends the border *x''*, corresponding in 100

position with the border x' of the stove base flange 10, the heart shaped ornaments w''' , having above the same the transversely oval shaped bars z , of increasing length upwardly, 5 the scrolls z' , inclosing said heart shaped ornaments and the end of said bars, and below said scrolls the representation of a leaf, z'' , of pondurate form, all shaped and arranged substantially as shown.

10 Having described my invention, what I claim is—

1. In the design for the stove the top section 1, composed of the parts 2, 3 and 4, all shaped, ornamented, proportioned and arranged together substantially as shown and described. 15

2. In the design for the stove, the cap plate 2, consisting of the parts a, b, c and c' , of the shape and ornamentation, substantially as 20 set forth.

3. In the design for the stove, the lower top plate 3, composed of the parts d, e, f, g and g' , of the shape and ornamentation, substantially as shown and described.

25 4. In the design for the stove, the intermediate top piece 4, consisting of the parts h and e' , of the shape and ornamentation, substantially as set forth and shown.

5. In the design for a stove, the door frame 30 plate consisting of the plain outline of the frame, 5, the parts i, j and j' , of the shape and ornamentation, substantially as shown and set forth.

6. In the design for a stove, the stove doors 6 composed of the parts k, e'', l, l' and the circular raised tablet m , having a plain border m' , and at one side of said tablet the ornamental latch n and keeper n' , all of the shape and ornamentation substantially as shown and described. 35

7. In the design for a stove, the fire pot ring 7, consisting of the parts o, o' and p , of the shape and ornamentation, substantially as shown and set forth. 40

8. In the design for a stove the foot rail 8, 45 having the parts q, r, s, s' and t , all shaped and ornamented substantially as described.

9. In the design for the stove, the base 9, consisting of the parts u, v, v', w, w', w'' and v'' , all of the shape and ornamentation, substantially as shown and set forth. 50

10. In the design for a stove, the base flange 10, composed of the parts $x, x', y, y', y'', y''',$ and y'''' , all shaped and ornamented, substantially as described and shown. 55

11. In the design for the stove, the legs, consisting of the outwardly and inwardly curved and transversely oval surfaced leg, the parts x'', w''', z, z' and z'' , all of the shape and ornamentation, substantially as described and shown. 60

GEORGE O. BERGSTROM.
